(No Model.)

G. F. KNOX.

ICE MAKING AND BLOCKING MACHINE.

No. 363,248.

Patented May 17, 1887.

UNITED STATES PATENT OFFICE.

GEORGE F. KNOX, OF SAN ANTONIO, TEXAS.

ICE MAKING AND BLOCKING MACHINE.

SPECIFICATION forming part of Letters Patent No. 363,248, dated May 17, 1887.

Application filed December 13, 1886. Serial No. 221,422. (No model.)

To all whom it may concern:

Be it known that I, GEORGE F. KNOX, of San Antonio, in the county of Bexar and State of Texas, have invented certain new and useful 5 Improvements in Ice Making and Blocking Machines, of which the following is a full, clear, and exact description, reference being had to the accompanying drawings, forming part of this specification, and in which—
10 Figure I is a side view of my improved ice-machine in vertical section, taken on broken line I I, Fig. II. Fig. II is a front view, one half in vertical section and one half in front elevation, taken on line II II, Fig. I; and Fig.
15 III is a horizontal section, taken on line III III, Fig. I, showing the refrigerating pan or tank filled with brine or other suitable uncongealable fluid and the evaporating-coils through which ammonia or other refrigerant 20 is forced.

My invention relates to an improved apparatus for the manufacture of clear ice by freezing the blocks from the top down, and my invention consists in features of novelty herein-
25 after fully described, and pointed out in the claims.

Referring to the drawings, in which similar figures of reference indicate like parts in all the figures, 1 represents the upper section of 30 one of my freezing-tanks, and 2 the lower section of the same.

3 are isolating-compartments that surround the refrigerating-pan and ice-forming tanks. These compartments may be filled with cork, 35 charcoal, or any other suitable material, to act as non-conductors and isolate the tanks from the atmosphere and all warm currents.

Shallow refrigerating-pans 4, immediately adjacent above the freezing-tanks, are filled 40 with brine or other suitable uncongealable liquid, and have located within the brine refrigerant coils 5, through which ammonia or other suitable evaporants or refrigerants are forced.

45 The upper portion of each of the freezing-tanks is divided into bottomless compartments or molds 6, in which the ice is formed, and which determine the shape and size of the blocks 7, making them convenient to handle 50 and of a uniform size for storage. The molds are surmounted by the aforesaid refrigerant-

pans, and their tops are of a slightly rounded or conical form at top, leaving tapering concavities in the bottom of the refrigerant-pan into which the cold brine has free entrance. 55 Each mold is provided with an air vent or pipe, 8, which rises from the center on the top of said molds and passes up through the brine in the refrigerating-pans to connecting-pipes 9 above, that discharge outside the apparatus, 60 at 10. These vent-pipes allow the free escape of the air from the molds (which are made slightly conical toward the entrance of the pipe) as the freezing-tanks are filled and the fresh water rises until it comes nearly in contact with the top of the molds in close proximity to the refrigerating-pan. The freezing process is thus begun in the upper parts of the bottomless molds and forces the dirt and air into the water beneath. The floors 11 of the 70 tanks are laid on an incline toward the front of the same, where said tanks are provided with drop doors or locks 12, which are made water-tight by means of rubber gaskets 13.

14 represents a force-pump that is of four-fold application, namely: for the conveyance of water from the hydrant or other source to fill the freezing-tanks; the transfer of water from one tank where blocks have been formed to the other preparatory to the formation of 80 blocks there; the forcing of the ammonia or other evaporant through the refrigerant-coils; and, lastly, the forcing of water through the tanks and wash-out pipes 15, that effect the purpose that their name denotes. 85

16 represents glass water-levels that indicate the height of the water in the course of filling the molds, to enable the operator to judge correctly in stopping the supply to the tank.

17 represents overflow-pipes, that form outlets for the superabundant water should the operator fail to stop the supply before it reaches the top of the molds. 90

18 represents spy-glasses, through which the operator observes the process of freezing and judges as to the completion of the formation of the blocks. 95

When the ice is of the desired thickness, the ammonia or other contents of the refrigerant-coils is shut off and sufficient warmth rises 100 from the water below, which is slightly above freezing-point, to loosen the blocks of ice in

the molds and allow them to float in the water beneath, which the operator can observe through the spy-glasses. The unfrozen water is then pumped from beneath the blocks into 5 adjoining or other tanks, with the exception of the residue that contains the dirt that has been discharged in the formation of the ice, and the settling, which are then removed through the wash-out pipes 15 under the efficient discharge of the force-pump. The blocks are thus gently lowered onto the inclined floor of the tank ready for being slid out through the doorway into the chute 19, and are then loaded up for shipment and storage.

15 In Figs. 1 and 2 are shown the lower tanks emptied of water, it having been pumped into the upper tanks. A catch of ice in blocks is seen to have left the molds above, as the remaining water not frozen is discharged and 20 the blocks are now resting on the inclined bottom of the tank ready to be slid down the incline and out through the doorway into the chute.

Some of the advantages of my "ice making 25 and blocking machines" are that they always freeze the water from the top down, and consequently produce pure ice, clear from dirt and center core, as they expel all foreign substances and air in the process of freezing into 30 the superfluous water beneath. The dirt then settles and is discharged through the washout-pipes, instead of, as is the case when the process of freezing takes place from all sides, when all the dirt and other foreign substances, including air, are driven toward the center, producing a foul imperfectly-frozen center-core, which is detrimental both to the purity and 35 lasting qualities of the ice. The impurities contained in such ice also cause an offensive taste and smell, and are a fruitful cause of disease among consumers.

Another advantage in my device is the ease with which the blocks are lowered as the water is withdrawn without abrasion against 45 each other onto the inclined floor of the tank, the inclination of which causes them to be easily slid forward into the chute, from which they are discharged onto the load; also, if it is desired to cause a slight movement in the 50 water during the process of freezing, as many prefer to thus expel the air from the congealing water, the same can be effected by a slight action of the force-pump.

I have described and shown twin ice-machines, and prefer so to construct them; but I do not so confine myself, for under some circumstances it may be of advantage to operate with several machines in connection, (where a large product is required,) from the ease with 60 which the surplus water can be conveyed from one to the other; and at other times it may be advantageous to use single machines or ones capable of producing, at one operation either a larger or smaller number of blocks, 65 according to the requirements of the establishment where the machines are operated. It is evident that I may thus far diversify the con-

struction and use of my machines without departing from the essential features of my invention.

70

I claim as my invention—

1. In an ice making and blocking machine, the combination of a non-conducting casing containing a freezing-tank having water supply and discharge pipes, molds supported in 75 said casing having open bottoms above the bottom of said tank and tapered upwardly from said open bottoms, and a refrigerating-pan over said molds for containing the refrigerating medium, substantially as and for the 80 purpose set forth.

2. The combination of a non-conducting casing containing a freezing-tank having water supply and discharge pipes, a water-tight diaphragm supported in said casing above the 85 bottom of said tank having downwardly-tapered hollows in its upper surface and corresponding upwardly-tapered molds in its under surface, and a refrigerating medium contained within the casing over said diaphragm 90 and filling the hollows in the latter, substantially as and for the purpose set forth.

3. The combination of a non-conducting casing, a diaphragm dividing the interior thereof into an upper refrigerant-chamber and a lower 95 freezing-chamber, water supply and discharge pipes connected with said freezing-chamber, and air-discharge pipes opening into said freezing-chamber near said diaphragm, substantially as set forth.

4. The combination of a non-conducting casing, a freezing-chamber having at top open-bottomed molds upwardly tapered, air-pipes opening into the tops of said molds, a refrigerating-pan over said molds, and water supply and discharge pipes for the freezing-chamber, substantially as set forth.

5. The combination of a non-conducting casing, a diaphragm within said casing dividing it into a lower freezing-chamber and an upper 110 refrigerating-pan, a non-congealing fluid in said pan, a coil in said fluid for the passage of a suitable refrigerant, means, substantially as described, for controlling the passage of the refrigerant in said coil, and water supply and 115 discharge pipes for the freezing-chamber, whereby when the passage of the ammonia or other refrigerant is interrupted the air of the water in the freezing-chamber will rise to the side of the ice blocks and assist in their 120 detachment from their molds, substantially as set forth.

6. The combination of a non-conducting casing, a freezing-chamber having a slanting floor, a door in the end of the casing at the lower 125 end of said floor, water supply and discharge pipes, molds above the floor of the freezing-chamber having air-pipes at top, and a refrigerating-pan over the freezing-chamber, whereby when the flow of the refrigerant is stopped 130 and the water drawn off from the freezing-chamber the ice blocks will settle to the floor thereof and be readily removed, substantially as set forth.

7. In combination with a non-conducting casing, a diaphragm containing downwardly-opening molds, a freezing-chamber, of which said diaphragm forms the top, a refrigerating-pan, of which said diaphragm forms the bottom, and a pipe leading from the tops of the molds and serving to carry off overflow and protect the molds from injurious expansion of the ice.
- 10 8. The combination of a non-conducting casing, a diaphragm dividing the same into a freezing-chamber and a refrigerating-pan, a non-congealing liquid in the latter, a coiled pipe in said liquid, water supply and discharge pipes for the freezing-chamber, and a pump 15 for charging and discharging the freezing-chamber, cleaning the latter, and forcing the ammonia through the refrigerating-coil, substantially as set forth.

GEORGE F. KNOX.
